UNITED STATES PATENT OFFICE.

FREDERICK H. WILLCOX, OF CHICAGO, ILLINOIS, ASSIGNOR TO FREYN, BRASSET & COMPANY, OF CHICAGO, ILLINOIS, A CORPORATION OF ILLINOIS.

CHIMNEY FOR HOT-BLAST STOVES.

1,387,528.

Specification of Letters Patent. Patented Aug. 16, 1921.

Application filed July 17, 1919. Serial No. 311,579.

To all whom it may concern:

Be it known that I, FREDERICK H. Willcox, a citizen of the United States, residing at Chicago, in the county of Cook and State 5 of Illinois, have invented certain new and useful Improvements in Chimneys for Hot-Blast Stoves, of which the following is a specification.

My invention relates to means in hot blast 10 stoves of the regenerative type and has particular reference to means for connecting the chimneys of such hot blast stoves and is applicable to stoves which have individual chimneys.

The primary object of my invention is the provision of connecting means for the chimneys having a passageway therethrough which will afford an increase of draft for the stove which is on gas, thereby carrying 20 off the products of combustion more readily and increasing the capacity of the hot blast stove.

A further object of my invention is the provision of connecting passageways for individual chimneys which will carry the products of combustion away from the hot blast stoves and will also keep the chimneys heated at all times whether the stove is on gas or on blast. Heretofore it has been the 30 practice to have individual chimneys for each hot blast stove and owing to the practice of keeping a stove on blast for a period of say two hours, and on gas for a period of say four hours, while the stove was on blast the chimney has cooled because of heat radiation to such a point that when the stove is put back on gas it takes considerable time for the chimney to become heated to a point where the products of combustion 40 will pass through readily. Therefore it requires a considerable time for the stove to become working full capacity because of the inability of the chimney to carry away the products of combustion. There are in 45 operation a great many hot blast stoves of this construction whose chimneys can be connected very easily and very cheaply and thus give these stoves a considerable increase in capacity.

Another and further object of my invention is the provision of connecting passageways for the chimneys of hot blast stoves which will give an increased draft for the stove, thus increasing its capacity by a very 55 great extent.

Another and further object of my invention is the provision of means which will connect the chimneys of hot blast stoves which is simple in operation and which can be easily and quickly installed and at a 60 minimum expense.

These and other objects of my invention will be more readily understood by those skilled in the art by reference to the accompanying sheet of drawings which is more 65 or less diagrammatic and which shows my invention as applied to the chimneys of hot blast stoves.

Referring specifically to the drawings, and in which like reference characters refer to 70 like parts throughout, hot blast stoves 10, 11 and 12 respectively are shown having chimneys 13, 14 and 15 respectively. The chimneys are individual and are set apart from the hot blast stoves. Connecting the 75 chimneys 13 and 14 is a member 16 having flared ends 17 and 18 immediately adjacent the stacks 13 and 14 respectively in order to avoid an abrupt right-angle turn for the products of combustion with the consequent 80 loss in velocity and an increase in frictional losses. A passage 19 is therefore provided extending from the chimney 13 through the chimney 14 and through which the products of combustion may pass. A similar member 85 20 having flared ends 21, 22 connecting the chimneys 14 and 15, so that a passageway 24 is formed which connects the chimneys 14 and 15, is provided. Butterfly valves 24 and 25 are interposed in the passages 19 and 90 23 for the purpose of shutting off the flow of products of combustion therethrough, if for any reason it may be desired to repair the chimneys or for any other reason desired. A passageway 26 connects the hot blast stove 95 10 with the chimney 13 and similar passages 27 and 28 respectively lead from the hot blast stoves 11 and 12. The products of combustion from the hot blast stoves are controlled by means of the usual chimney 100 valves (not shown) interposed in these passages in the usual manner.

In operation the device is exceedingly simple, requiring no attention; however, if desired, when the stove is first put on blast 105 the butterfly valves 24 and 25 may be closed until the system is started and then it could be opened so that the products of combustion will pass into all of the chimneys regardless of which stoves are on gas.

As illustrating the invention, we will say that stoves numbers 10 and 12 are on gas while number 11 is on blast. The passage 27 leading from the stove 11, of course, is closed while the passages 26 and 28 are open, allowing the products of combustion to pass into the base of the chimneys 13 and 15 and cross through the passages 19 and 23, the butterfly valves 24 and 25 being open and a portion of the products of combustion will therefore pass outward through the stack 14. It will be evident, therefore, that by means of my invention the full chimney capacity of three stoves is available at all times regardless of whether one or more of the stoves is on gas at the same time.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. In combination with hot blast stoves, of chimneys and means having passages therethrough connecting the chimneys.
2. In combination, hot blast stoves, chimneys for said stoves, and passages connecting the said chimneys.
3. In combination, hot blast stoves, chimneys for said stoves through which the products of combustion may pass, means for connecting said chimneys having passages therethrough, and means in said passages for closing the passages.
4. In combination hot blast stoves, of chimneys for said stoves, means for connecting the chimneys, the said means having flared ends whereby the products of combustion are prevented from making abrupt turns in passing from one chimney to another.

Signed at Chicago, Illinois, this 27 day of June, 1919.

FREDERICK H. WILLCOX.

It is hereby certified that the State of incorporation of the assignee in Letters Patent No. 1,387,528, granted August 16, 1921, upon the application of Frederick H. Willcox, of Chicago, Illinois, for an improvement in "Chimneys for Hot-Blast Stoves," was erroneously given as "Illinois," whereas said State should have been given as *Maine*, as shown by the record of assignments in this office; and that the said Letters Patent should be read with this correction therein that the same may conform to the record of the case in the Patent Office.

Signed and sealed this 4th day of October, A. D., 1921.

[SEAL.]

KARL FENNING,

Acting Commissioner of Patents.
